UNITED STATES PATENT OFFICE

2,446,199

STARTING CIRCUIT FOR GASEOUS DISCHARGE DEVICES

Paul W. Stutsman, Needham, Mass., assignor to Raytheon Manufacturing Company, Newton, Mass., a corporation of Delaware

Application March 27, 1946, Serial No. 657,423

4 Claims. (Cl. 315—101)

1

This invention relates to gaseous electrical discharge devices of the type having thermionic cathodes, and more particularly to means whereby such discharge devices may be quickly started from a commercial supply line of 110 volts.

In gaseous discharge devices of certain types, heating current is supplied to the cathodes only during the initial starting period. In order to disconnect the heating current after firing the tube, various expedients have been used. Time delay relays or bi-metallic thermal strips have been associated with the heating circuits, but these involve movable contact points which deteriorate in a short time, and furthermore they do not insure that the heating current will be discontinued immediately upon the firing of the device. Also, heavy resistors may be interposed in the heating current circuit. However, these tend to limit the heating current during the starting period as well as after the tube has fired.

It is among the objects of the present invention to provide a circuit arrangement for gaseous discharge devices in which the cathode is rapidly heated on starting and in which the heating current is immediately discontinued upon the firing of the device.

The above and other objects and features of the invention will be made fully apparent to those skilled in the art from a consideration of the following detailed description taken in conjunction with the accompanying drawing which shows a diagrammatic illustration of an electrical circuit embodying the present invention.

Referring to the drawing, reference numeral 4 indicates a gaseous discharge device including an anode 5 adapted to be connected to one of the terminals 6 of a commercial supply line through a resistor 8 which may be of the order of 100 ohms. The discharge device 4 is also provided with a thermionically emissive cathode 9 which is connected to the other terminal 7 of the power supply line through a load resistance 10 which may be of the order of 2500 ohms. A condenser 11 of relatively large capacity is shunted across the resistance load 10. In order to supply heating current to the cathode 9, one terminal of the filament circuit is connected to the terminal 6 through a trigger tube 12. The tube 12 includes an anode 13 connected through a small resistor 14, which may be of the order of six ohms, to the supply line leading to the anode 5, at a point between the terminal 6 and the resistor 8. The cathode 15 of the tube 12 is connected to one side of the filament 9 and through this filament to the resistance load 10 and condenser 11. The tube

12 is also provided with a starting electrode 16 of the type adapted to establish a glow discharge with the cathode 15. The starting electrode 16 is connected to the plate 13 of the tube 12 through a relatively large resistor 17 which may be of the order of 100,000 ohms.

In the operation of the circuit described in the foregoing, when the terminals 6 and 7 are connected to a commercial supply line by the closure of a suitable switch, the starting electrode 16 of the tube 12 and the main anode 13 are initially at substantially the same potential relative to the cathode 15. However, when a glow discharge is established between the starting electrode 16 and the cathode 15, the potential of the electrode 16 is substantially reduced as compared with the potential at the anode 13, due to the current flow through the resistor 17. The glow discharge initiates a discharge between the anode 13 and the cathode 15, and a heavy flow of current through the cathode-anode circuit of the tube is effected. This current flows through the thermionic cathode 9 of the tube 4 and the condenser 11. The heavy flow of heating current through the thermionic cathode 9 rapidly heats this cathode to such a temperature that the tube 4 fires, permitting the flow of current from the line 6—7 through the load 10. Upon the firing of the tube 4, the potential drop across this tube becomes relatively small, and the tube 12 is extinguished. Thereafter the cathode 9 is heated by ionic bombardment sufficiently to maintain thermionic emission, and thereby maintain the discharge through successive cycles.

35 The circuit described in the foregoing insures that an ample heating current will initially flow through the thermionic cathode 9 sufficient to heat this cathode rapidly and insure a prompt discharge through the tube 4. Upon the firing of the tube 4, the circuit insures that the heating current to the cathode 9 will be instantly discontinued.

45 While there has been herein described a preferred embodiment of the invention, other embodiments within the scope of the appended claims will be apparent to those skilled in the art from a consideration of the form shown and teachings herein.

What is claimed is:

50 1. A circuit for initiating an arc in a gas discharge device of the type including an anode and a heated cathode comprising a source of current connected across and adapted to supply operating potential to said device, a tube of the type 55 having relatively low voltage starting character-

istics, the anode of said tube being connected to the anode of said discharge device and to one terminal of said source, and the cathode of said tube being connected through the heating circuit of the cathode of said discharge device to the opposite terminal of said source, a resistance load connected in the discharge circuit of said device, and a capacitor in shunt with said load.

2. A circuit for initiating an arc in a gas discharge device of the type including an anode and a heated cathode comprising a current source connected across and adapted to supply operating potential to said device, a tube of the type in which a glow discharge initiates an arc discharge through the anode-cathode circuit thereof, the anode of said tube being connected to the anode of said discharge device and to one terminal of said source, and the cathode of said tube being connected through the heating circuit of the cathode of said discharge device to the opposite terminal of said source, a resistance load connected in the discharge circuit of said device, and a capacitor in shunt with said load.

3. A circuit for initiating an arc in a gas discharge device of the type including an anode and a heated cathode comprising a current source connected across and adapted to supply operating potential to said device, a tube of the type having a pair of electrodes between which a glow discharge occurs upon the application of a potential thereto for initiating an arc discharge through the anode-cathode circuit thereof, the anode of said tube being connected to the anode of said discharge device and to one terminal of said

source, and the cathode of said tube being connected through the heating circuit of the cathode of said discharge device to the opposite terminal of said source, a resistance load connected in the discharge circuit of said device, and a capacitor in shunt with said load.

4. A circuit for initiating an arc in a gas discharge device of the type including an anode and a heated cathode comprising a current source connected across and adapted to supply operating potential to said device, a tube of the type having a pair of electrodes between which a glow discharge occurs upon the application of a relatively low potential thereto for initiating a substantially larger current flow through the anode-cathode circuit thereof, the anode of said tube being connected to the anode of said discharge device and to one terminal of said source, and the cathode of said tube being connected through the heating circuit of the cathode of said discharge device to the opposite terminal of said source, and a resistance load connected in the discharge circuit of said device.
